UNITED STATES PATENT OFFICE

143,606

DESIGN FOR A SAFE

John V. McGunn, Chicago, Ill.

Application August 20, 1945, Serial No. 121,498

Term of patent 14 years

(CL D69—1)

To all whom it may concern:

Be it known that I, John V. McGunn, a citizen of the United States, residing at Chicago, in the county of Cook and State of Illinois, have invented, a new, original, and ornamental Design for Safes, of which the following is a specification, reference being had to the accompanying drawing, forming part thereof.

The figure is a perspective view of a safe, showing my new design.

I claim:

The ornamental design for a safe, as shown.

JOHN V. McGUNN.
